UNITED STATES PATENT OFFICE.

WILLIAM L. NICOLS, OF TUSCUMBIA, ALABAMA.

TOY CANNON.

1,352,681.

Specification of Letters Patent. Patented Sept. 14, 1920.

Application filed August 29, 1919. Serial No. 320,737.

To all whom it may concern:

Be it known that I, WILLIAM L. NICOLS, a citizen of the United States of America, residing at Tuscumbia, in the county of Colbert and State of Alabama, have invented certain new and useful Improvements in Toy Cannon, of which the following is a specification.

This invention relates to toy cannons and has for its chief object to utilize the catapult principle for the projection of a ball or missile in combination with an agency adapted to produce a report or explosive noise simultaneously with the projection of the missile.

5 My preferred arrangement for producing the report or explosive noise is a pop gun which ejects a stopper or cork simultaneously with the release of the catapult arm so that the pop gun and catapult function at the same time, but any agency that will make a report may be enjoyed. I thus produce a toy cannon, which will produce a report without being at all dangerous for use by children.

5 A further feature of my invention is the arrangement of all the mechanism in a housing which may simulate a cannon or field weapon and which will protect the moving elements so that a child can not be injured thereby.

My invention further comprises the novel details of construction and arrangement of parts which in their preferred embodiment only are illustrated in the accompanying drawings in which:—

Figure 1 is a vertical sectional view showing the parts in position preparatory for releasing the catapult and exploding the pop gun.

Fig. 2 is a vertical sectional view taken on the line 2—2 of Fig. 1.

Figs. 3 and 4 are vertical sectional views taken on the lines 3—3 and 4—4 of Fig. 1 respectively.

Similar reference numerals refer to similar parts throughout the drawings.

In the preferred embodiment of my invention, illustrated in the drawings, I show a housing comprising a flat base 1 with a vertical front wall 2 joined to side walls 3

which are curved along their rear edges and covered with a bent metal back wall 4 which extends from the rear edge of the base vertically and then is bent sharply forward at 5 and then continues on a concentric curve 55 to a point near the top of the front wall 2 where it flattens out and is joined to top edge of said wall. It is also connected to a vertical partition 6 parallel with the wall 2 and spaced therefrom, the partition and front wall having notches in their top edges for the escape of the projectile. The notch in the front wall receives the barrel 8, the top of which is formed by a horizontal forward extension of the wall 4 and the sides of which are formed by integral downwardly bent side flanges 7 carried by the extension 8. At the rear ends of these flanges I place guide plates 9, which project about an inch behind the partition 6. In the rear of the partition 6 near its lower end is a cross rod 70 10 fixed in the side walls 3 and having journaled thereon a U-shaped frame formed by bent wire, the sides of which pass upwardly through the top of the casing or housing and are connected above by a cross arm or 75 handle 11. This frame near its upper end within the housing, carries a cross arm 12, which is normally seated in a transverse groove 13 in the top of the partition 6 and this cross-arm is adapted to engage the catapult arm 14 near its free end. This catapult arm is formed by a metal bar pivoted at its lower end on the cross rod 10, which is flattened on each side at 15 to hold the catapult arm to movement in a fixed plane. The 80 arm at its free end carries a ball socket 16 and a latch 17 and is engaged by the transverse cross arm 18, connecting the free ends of two coil springs 19, which are arranged to work in notch-outs 20 at each side of the 85 partition 6 and are made fast at the inner ends of their coils to partition 6. The coil springs are brought under compression when the swinging frame 11 is pressed rearwardly and downwardly, to permit which, the casing 4 is formed with elongated slots 21 extending from the top of the back wall 4 to its portion 5 and as the frame 11 is thus moved down the cross member 12 carries 90 95

the catapult arm with it until the latter reached its full line position shown in Fig. 1, with the springs 19 under full tension when the latch 17 will automatically engage 5 a trigger mechanism comprising a latch 22 and trip means therefor which will be later described. The latch 22 which is pivoted to low transverse partition 23 extending upwardly from the base and joined at its ends 10 to the side walls. The latch is pivoted near its upper end and its lower end is engaged by a spring 24 which forces it into arm engaging position. In front of the lower free end of the latch is a arm 25, forming part 15 of the trigger trip means pivoted near its center on a vertical pin 26, which at its lower end turns in a step bearing in the base 1 and at its upper end turns in a bearing in the partition 23. The other end of this trip 20 arm is disposed in the path of a trip pin 28 depending from the squared outer end of the reciprocable trigger 29. This squared end of the reciprocable trigger works through squared openings in the rear wall 4 and the 25 partition 23 at its outer end is provided with a suitable handle or grip 30 by means of which it can be reciprocated. At its inner end the trigger carries a plunger 31, which works in a pop gun barrel 32 that is made 30 fast in the front wall 2 and the partition 6 and which at its outer end is adapted to receive a cork or equivalent stopper 33 that is connected by a cord or flexible element 34 to the base. The trigger also carries a pin 35 to limit its inward travel into the barrel 32.

The barrel for the ball projected by the catapult is left open below as is seen more clearly in Fig. 4 and on its top is provided 40 with the two sights 35.

In operation assuming the trigger 29 to be drawn back and the catapult arm in vertical position against the partition 6, to operate the cannon the handle 11 is grasped and 45 drawn downwardly through the slots 21 carrying with it the catapult arm until the latter is caught and held by the latch 22. A ball or projectile is then inserted in the socket 16 through a slot or opening 36 in the 50 rear wall 4 and the cork or stopper is inserted in the outer end of the pop gun barrel 32. The springs 19 will be held under substantial tension while the latch holds the catapult arm, and as soon as the catapult arm 55 has been caught by the latch, the frame 11 is returned to vertical position in which it is normally held by engagement with a knuckle bearing 37 on the partition 6 which serves as a friction catch to engage the cross 60 arm 12 on the frame 11. To fire the cannon, the trigger plunger is operated, being forced inwardly, until its trip 28 engages the trip arm 25 and pulls the latch to release the catapult arm at the same time that the plunger 65 ger 31 ejects the cork or stopper with a loud

report from the pop gun barrel 32. The catapult arm as it swings forward and upwardly will in the manner well understood in the art project the ball through the barrel 8, the guide plates 9 preventing lateral diversion as the ball approaches the barrel. 70

The arrangements of parts and their detailed constructions can be widely varied without departing from the principles of my invention which involve essentially the 75 combination of a missile projector and a pop gun which are coördinated to function at the same time and thus to simulate the report which accompanies the projection of the ball by guns or cannons. 80

Having thus described my invention what I claim as new and desire to secure by Letters Patent is:—

1. In a toy cannon, a catapult comprising a spring-pressed pivoted arm having means for holding a missile at its free end, a stop to arrest said arm as it approaches vertical position, and a barrel to receive and direct the missile when projected from the catapult arm. 85

2. As an article of manufacture, a toy comprising in combination a base, a catapult and a pop gun mounted on said base, latch means to hold the catapult set, a common reciprocable element carrying a plunger for the pop gun, and a trip for the latch so related as to produce simultaneous operation of pop gun and catapult, substantially as described. 90

3. As an article of manufacture, a toy comprising a housing, a catapult operable within the housing, a latch means to hold the catapult set, a pop gun mounted in the housing near the base thereof, a plunger for the pop gun reciprocable through the housing, and trip means on the plunger to release the latch means substantially simultaneously with the operation of the pop gun. 95

4. In a toy cannon, a catapult formed by a pivotal spring-pressed arm adapted to carry a missile at its free end, a housing for the catapult comprising a stop for the arm, a barrel in advance of the stop through which the catapult arm is adapted to project said missile, and a trigger means for the catapult, there being an opening in the housing for loading the catapult arm when engaged by said trigger means. 100

5. In a toy cannon, a catapult, a housing inclosing the catapult, an arm pivoted in the housing substantially concentric with the catapult and movable to engage and set the catapult, trigger means to hold the catapult under tension in set position, means to hold said arm in its initial position, and a stop for the catapult adapted to protect said arm from injury by being struck by the catapult, there being a slot in said housing through which the free end of said arm projects for manual operation. 105

6. In a toy cannon, a housing, a catapult mounted in and protected throughout its travel by said housing, a stop to arrest the catapult, latch means to hold the catapult under tension, a barrel connected to the housing in position to receive and direct the missile as it leaves the catapult after

movement of the latter is arrested, and an element operable from without the housing and adapted to releasably engage and set 10 the catapult under tension.

In testimony whereof I affix my signature.

WILLIAM L. NICOLS.
